UNITED STATES PATENT OFFICE.

OTTO KERSCHT, OF DETROIT, MICHIGAN.

MULTIPLE-CYLINDER EXPANSIVE-TYPE ENGINE.

1,083,405.

Specification of Letters Patent.

Patented Jan. 6, 1914.

Application filed April 10, 1913. Serial No. 760,109.

To all whom it may concern:

Be it known that I, OTTO KERSCHT, a citizen of the United States of America, residing at Detroit, in the county of Wayne and State of Michigan, have invented certain new and useful Improvements in Multiple-Cylinder Expansive-Type Engines, of which the following is a specification, reference being had therein to the accompanying drawings.

This invention relates to improvements in engines and more particularly to a construction in which the motive fluid is used expansively and which is especially adapted for internal combustion engines of the "semi-Diesel" type.

The object of the invention is to secure a maximum power from the fuel consumed and to provide a balanced arrangement of pistons and reciprocating parts which will give a compact construction and which is such that reversal of the operation may be quickly and easily effected.

A further object is to provide certain new and useful features in the construction and arrangement of parts all as hereinafter more fully described.

To these ends the invention consists in the matters hereinafter set forth and more particularly pointed out in the claims reference being had to the accompanying drawings in which,

Figure 1, is a side elevation of an engine embodying the invention; Fig. 2, is a transverse section through the cylinders of the same upon the line II—II of Fig. 3; Fig. 3, is a longitudinal section through the cylinders on the line III—III of Fig. 2; Fig. 4, is a transverse section on the line IV—IV of Fig. 3; Fig. 5, is a transverse section on the line V—V of Fig. 3; Fig. 6, is a section on the line VI—VI of Figs. 4 and 5; Fig. 7, is a section on the line VII—VII of Figs. 2 and 4; Fig. 8, is a section on the line VIII—VIII of Figs. 2, 4 and 5; Fig. 9, is a detail of one of the motive fluid controlling valves, showing the same in longitudinal section; Figs. 10, 11 and 12 are cross sections of the same showing the parts in their different positions of operation, and Figs. 13, 14 and 15 are detail views of the two sleeves of the valves separated and in their relative position corresponding to the position of the parts in Figs. 10, 11 and 12 respectively.

The engine comprises a head or casing 1 and a base frame 2 which is formed with

bearings for a crank shaft 3. The case is formed with a bore at each side forming main cylinders 4 and 5 in each of which are two pistons 6 and 7 in opposed relation and adapted to be operated by fluid pressure in the cylinders between the opposed ends of the pistons and between the outer ends of the pistons and the ends of the cylinders. The pistons 7 are connected by means of hollow piston rods 8 and connecting rods 9 with the crank shaft 3, and the pistons 6 are connected with said crank shaft by means of piston rods 10 passing through the hollow rods 8 and connected at their lower ends to connecting rods 11. The casing 1 is also formed with a bore positioned midway between the cylinders 4 and 5 and forming an auxiliary cylinder 12 of larger diameter than the main cylinders. In this auxiliary cylinder are opposed pistons 13 and 14 operated in the same manner in which the main pistons are actuated, the piston 14 being connected with a crank of the crank shaft 3 by means of a tubular piston rod 15 and connecting rod 16, and the piston 13 being connected with the crank shaft by means of a piston rod 17 extending through the hollow rod 15 and connected at its lower end by means of a connecting rod 18 with the crank shaft.

Each of the cylinders 4 and 5 is provided with two pairs of exhaust ports 19 and 20 adapted to be covered and uncovered by the pistons and allow the products of combustion or motive fluid to escape through passages 21 and 22, each passage 21 leading to a valve 23 formed with a passage adapted to connect the passages 21 with passages 24 and 25, the passages 25 leading to ports 26 in the outer ends of the cylinder 12 and the passages 24 leading to a common port 27 intermediate the ends of the cylinder at each side thereof between the adjacent ends of the pistons 13 and 14. The passages 22 lead to valves 28 having suitable passages for connecting the passages 22 with suitable passages 29 leading to ports 30 in the outer ends of the cylinder 12 and to also connect said passages 22 with passages 31 leading to a common port 32 at each side and intermediate the ends of the cylinder 12 between the adjacent ends of the pistons 13 and 14. By turning the valves 23 and 28 in timed relation to the movement of the several pistons, the products of combustion or motive fluid are alternately exhausted from the combus-

tion chambers of the main cylinders through the several passages into the auxiliary cylinder, either between the opposed ends of the pistons in said cylinder or between the outer ends of said pistons and the outer ends of the cylinder. From the auxiliary cylinder the exhaust escapes through exhaust ports 33 into an exhaust passage 34 extending parallel with the cylinder and out through a suitable exhaust pipe 35 secured to the end of the casing or head 1.

There is a pair of valves for each pair of outlet ports in the main cylinders, a valve 23 and a valve 28 being arranged side by side with a short space between them constituting one pair of valves. To operate the four pairs of valves in timed relation to the movement of the several pistons, a rack member 36 (see Fig. 6) is guided in suitable ways 37 provided therefor in the casing and reciprocates in a suitable chamber in the casing at one side of the several cylinders. The ends or stems of the valve members 23 and 28 extend into and have a bearing in said chamber where they are each provided with a mutilated gear or formed with teeth 38 adapted to be engaged by teeth on the rack member 36 which teeth are so arranged that they will engage the teeth upon the valve member when the rack member is reciprocated and turn the valves approximately a quarter of a revolution with an intermittent movement and in the proper direction to properly connect up the passages between the main cylinders and the auxiliary cylinder. Rack bars 39 and 40 have a bearing in the casing and extend therethrough between the valves of each pair of valves at each side of the auxiliary cylinder and project through the ends of the casing. The valves are each provided with a gear 41 to engage the rack bars which are always in mesh therewith and thus the two pairs of valves and the valves of each pair at each side of the auxiliary cylinder, are connected up by a rack bar to turn in unison. An actuation of one of the valves will therefore actuate all of the valves of the two pairs of valves at one side of the auxiliary cylinder, but the rack member 36 is preferably so constructed and provided with teeth so arranged that corresponding valves of each pair of valves will be simultaneously operated by the rack member.

The rack member 36 is automatically reciprocated in timed relation to the movement of the several pistons, by means of pistons 42 within the cylinders 43 (see Fig. 6) located adjacent to one side of the main cylinders 4 and 5 and intermediate the ends thereof. These cylinders are arranged with their longitudinal axes extending at right angles to the longitudinal axes of the main cylinders and the pistons in these cylinders

are rigidly connected by means of a piston rod 44 to which the rack member 36 is rigidly secured intermediate the ends of said rod. Products of combustion or motive fluid is admitted to the inner ends of the cylinders 43 through passages 45 (see Figs. 2 and 3) opening into the main cylinders adjacent to the inner ends of the strokes of the main pistons. These passages 45 give a free communication between the main cylinders and the cylinders 43.

75

Each of the main cylinders is provided with a fluid inlet port 46 at each end and similar ports 47 intermediate its ends. The ports 46 are controlled by fluid inlet valves 48 and the ports 47 by valves 49. All of these valves are simultaneously operated in the proper manner and in timed relation to the movement of the several pistons, by means of a gear 50 on each valve in mesh with the rack bars 39 and 40, which in turn are reciprocated by the several pairs of valves 23 and 28.

80

Adjacent to the side of the main cylinders opposite that at which the supplemental cylinders 43 are located, are pump cylinders 51 (see Figs. 2 and 7) in the casing and pump pistons 52 in these cylinders are connected by a rigid piston rod 53 to operate in unison. A rack frame 54 is mounted in suitable guides in the casing and is secured to the rod 53 to reciprocate said rod and actuate the pump pistons. The rack frame 54 is provided with teeth 55 adapted to be engaged by suitable mutilated gears or teeth 56 upon the extreme upper ends of the valve members 23 and 28 of the two pairs of valves at each side of the auxiliary cylinder. When these valve members are turned as previously described, their teeth 56 will engage the teeth of the rack frame 54 and actuate 105 said frame to reciprocate the pump pistons in timed relation to the movement of the several main or power pistons. Oil, gasoline or other motive fluid is admitted to the pump cylinders 51 through suitable passages 110 57 (see Fig. 2) communicating with any suitable supply, not shown, and the oil is discharged from said pump cylinders through passages 58 into the upper ends of the oil valves 49 which are preferably tubular in form and are provided with suitable openings to register with the oil passages leading to the ports 47. Oil is also conducted from each pump cylinder through pipes or passages 59 into the upper ends of the tubular oil valves 48 for supplying oil to the ends of the main cylinder at the opposite side of the casing. Oil is thus forced by one pump piston to the valves controlling the inlet of fuel to the explosion chamber 120 between the adjacent ends of the pistons in one of the power cylinders and at the same time forces oil to the valves controlling the

115

120

125

inlet of fuel to the outer ends of the power cylinder at the opposite side of the casing.

For supplying fresh air to the main cylinders when the engine is used as a combustion engine, to maintain combustion in the cylinders, and to heat such air and force it into the cylinders under pressure, the casing adjacent to the pump cylinders 51 is formed with cylinders 60 in which are pistons 61 secured to and movable with the pump pistons 52 and connecting rod 53. When the oil pumps are operated as previously described the pistons 61 will also be actuated and force air from their cylinders through suitable check valves 62 into a passage or chamber 63 which opens into a space 64 extending across the casing 1 and around all of the cylinders, forming cooling jackets for the cylinders.

At one side of the power cylinders and adjacent to each end of each cylinder, is an air compression cylinder 66, each containing a piston 67 and arranged with its longitudinal axis extending at right angles to the longitudinal axis of the power cylinder. The pistons in the compression cylinders 66 adjacent to the ends of the power cylinder 4 are connected to the pistons in the compression cylinders adjacent to the ends of the power cylinder 5 by means of rigid connecting rods 68 so that the piston in the cylinder at one side of the casing is connected to and moves simultaneously with the piston in the opposing cylinder at the other side of the casing. Each connecting rod 68 is formed with teeth to engage a gear 65 mounted to turn freely on a fixed stud on the adjacent wall of the casing and the outer sides of the rack 36 are also formed with teeth to engage these gears 65 at their opposite side. The rack member 36 and the piston rods 68 are thus connected by the interposed gears 65 to move simultaneously in opposite directions and therefore when the pistons 42 are moving in one direction, the pistons 67 are moving in an opposite direction. The outer ends of the power cylinders are connected to the inner ends of the compression cylinders 66 by open passages 69 and said compression cylinders communicate with the air space 64 through check valves 71 (see Fig. 5) which open to let the air in said cylinders from the space when the pistons 67 are actuated and operate to draw in air through said valves. Similar check valves 71 (see Fig. 2) are provided to admit air from the jacket space into the cylinders 43. Air is thus supplied by the compression cylinders 43 and 66 to the ends of the main cylinders and to said cylinders intermediate their ends, to correspond with the order in which the explosions take place therein.

To shift the rack bars 39 and 40 and manually turn the several oil and motive fluid

valves so that the operation of the engine 65 may be reversed, a shaft 72 is mounted in brackets on the end of the casing and provided with pinions 73 to engage rack teeth 74 on each of the rack bars 39 and 40 (see Fig. 3). A hand wheel 75 (see Fig. 1) is 70 provided on the end of the shaft 72 to turn the same and by grasping this hand wheel the operator may quickly turn the shaft and move both rack bars simultaneously in a longitudinal direction and by reason of the engagement of the rack bars with the gears on the several valves turn said valves simultaneously. The flow of the exhaust from the main into the auxiliary cylinder is thus changed and the timing of the gasoline inlet 80 is correspondingly shifted, said gasoline valves being turned to closed position by such manual movement of the rack bars and supplemental oil valves 76 being simultaneously opened to admit charges to the 85 main cylinders at the proper ends thereof to give a reversing impulse. The opening of the valves 76 simultaneously with the closing of the valves 48 and 49 is accomplished by means of bevel gears 77 on the lower ends 90 of said valves 76 in mesh with the gears 78 on the shaft 72, which shaft is adapted to move longitudinally in its bearings so as to disengage its gears from the gears 77 and thus permit the shaft to be turned by the 95 normal reciprocation of the rack bars without actuating said supplemental valves.

To permit the escape of the pressure which is behind the pistons driving them at the time of reversal and thus allow the charge 100 admitted by the auxiliary valves 76 to act in an opposite direction, an auxiliary exhaust valve 79 is provided adjacent to each of said valves and these exhaust valves are turned simultaneously with the actuation of the 105 valves 76 by means of gears 80 on the outer ends of said valves in mesh with idler gears which transmit motion therefrom to like gears 81 (Fig. 8) on the adjacent end of the exhaust valves. These exhaust valves are 110 tubular in form and provided with lateral openings to register with passages leading to ports 82 in the main cylinders which ports are properly positioned to allow the contents of the cylinders to escape at the proper time. 115 A passage 85 connects an exhaust opening in the side of each valve with the main exhaust passage 34. The fuel valves 76 are also tubular in form and are each supplied with fuel through a passage 83 (see Figs. 2 and 120 8) which communicates with the passage 58 leading to the adjacent valves 49, said auxiliary or reversing valves 76 being also formed with side openings to register with passages leading to ports 84 opening into 125 the main cylinders at such points that they will be uncovered by the pistons at the proper time to admit fuel at the sides of the

pistons opposite that from which the contents of the cylinders is permitted to escape by the opening of the exhaust valves 79, and to thus cause a reversal of the operation of 5 the engine.

The main fuel valves 48 and 49 each comprise, as shown in Figs. 9 to 15 inclusive, an outer sleeve 85 which fits within a suitable bore in the casing and an inner sleeve 10 86 fitting therein and adapted to be turned therewith and relative thereto to open and close ports 46 and 47 leading to the main cylinders. Fitting within the inner sleeve is a tube 87 having an open upper end into 15 which the motive fluid flows from the passage 58. This tube has an opening or slot 88 in one side for the escape of the fluid which is adapted to register with similar slots 89 in opposite sides of the inner sleeve. 20 The outer sleeve is also cut away at one side as at 90 and provided with a slot 91 near its opposite side properly located to register with the slots in the inner sleeve and with the passage in the wall leading to the port 25 47. The outer sleeve is provided upon its lower end with a gear or gear teeth 92 and the inner sleeve which projects through the lower end of said outer sleeve is likewise provided with a gear 93, both gears being of 30 a proper size to be engaged simultaneously by one of the rack bars 39 and 40 and turned thereby when said bar is moved longitudinally during the normal operation of the engine, as described or when manually operated 35 through the medium of the hand wheel 75 to reverse the operation of the engine and thus automatically control the admission of charges to the cylinders in timed relation to their movements.

40 When the rack bars 39 and 40 are moved manually, to turn their two sets of valves 23 and 28 and thus change the flow of the exhaust from the main cylinders into the expansion cylinders, from one set of passages to the other, the fuel valves are also turned by said bars, and in order that the fuel may be admitted in proper timed relation during the normal running of the engine and also while running in a reverse 45 direction, suitable means are provided for turning and setting said sleeves 85 and 86 of each valve relatively by the operation of the bar engaging the gears of said sleeves. Each gear 92 and 93 on the sleeve is mutilated, that is one side is cut away or left blank so that only one of the sleeves will 50 be turned by the reciprocation of the adjacent rack bar when the same is actuated by the running of the engine. When the bar 55 is shifted for reversing the engine, both sleeves are turned relatively by means of a pin 94 on the gear 92 to engage a slot 95 in the gear 93.

The sleeves being in the position shown

in Fig. 13 with the engine running forward, 65 the sleeve 85 remains stationary as the teeth of its gear do not engage the rack bar and the sleeve 86 is turned one fourth of a revolution by said bar to properly control the admission of fuel to the cylinder. Upon the 70 reversal movement of the rack bar, said inner sleeve is turned one half of a revolution, bringing its mutilated side opposite the bar and by the engagement of the end of its slot 95 with the pin 94, turning the outer 75 sleeve one fourth of a revolution and thus bringing its gear 92 into engagement with the bar so that upon reciprocation of the bar automatically by the actuation of the engine, the outer sleeve will be rotated back 80 and forth through one quarter of a revolution until the bar is again manually moved to reset the sleeves. The amount of fluid which will be admitted by each valve may be regulated by adjusting or turning the 85 tube 87 therein by any suitable means such as a gear 96 (see Fig. 9) on its lower end which extends through the lower end of the inner sleeve and which gear is turned by a rack bar 97 or any other suitable means. 90 If found desirable, the supply of a lubricant to the cylinders may be controlled by rotary valves actuated in a like manner from the reciprocable rack bars 39 and 40.

If found desirable a block 98, (see Figs. 2, 95 5 and 6) may be provided in one end of each of the cylinders 43 and 66 to be adjusted therein and increase or decrease the capacity of its compression space as desired, said blocks being simultaneously adjusted by 100 suitable levers as indicated at 99 in Figs. 2 and 5 or any other suitable means. The air inlet valves 70 and 71 for the cylinders 66 and 43 respectively, may be held closed to 105 shut off the supply of air to said cylinders, by means of rods 100 having screwthreaded engagement with the casing and extending inward into contact with the outer side of each valve, said rods being adjusted by means of hand wheels on their outer ends. 110 A passage 101 may also be provided in the casing adjacent to each of the main cylinders extending longitudinally thereof and communicating with said cylinders through 115 ports 102 therein properly located to be covered and uncovered by the main pistons at the proper time to admit air under pressure thereto for the purpose of forcing out the burned gases and cleansing the cylinder, said passages being in communication 120 with the cylinders 43 and 66 to receive air therefrom through ports 103 therein controlled by the piston in said cylinders.

Obviously changes may be made in the construction, arrangement and combination 125 of parts without departing from the spirit of my invention and I do not therefore limit myself to the particular construction shown.

Having thus fully described my invention what I claim is:—

1. In an engine, the combination of a plurality of main cylinders, opposed pistons in each cylinder, an auxiliary cylinder, opposed pistons in the auxiliary cylinder, means for conducting the exhaust from the main cylinders into the auxiliary cylinder between the pistons therein and between the ends of the pistons and the ends of the cylinder, and means operated in timed relation to the movement of the pistons for controlling the passage of the exhaust from the main to the auxiliary cylinders.
2. In an engine, the combination of a plurality of main cylinders, an auxiliary cylinder, passages for conducting the exhaust from the main cylinders into the auxiliary cylinder, valves controlling said passages, pistons in the several cylinders, valves controlling the inlet of motive fluid to the main cylinders, and means operating in timed relation to the movement of the pistons for actuating all of the valves, said means being adapted to be manually operated to actuate the valves and reverse the operation of the engine.
3. In an engine, the combination of a main cylinder, a pair of opposed pistons in said cylinder, an auxiliary cylinder, opposed pistons in said auxiliary cylinder, a plurality of passages for conducting the exhaust from the main cylinder into the ends of the auxiliary cylinder and into the auxiliary cylinder intermediate its ends, a plurality of valves for controlling said passages, a reciprocable member for actuating the valves, and means for reciprocating the member in timed relation to the movement of the pistons.
4. In an engine, the combination of a main cylinder, opposed pistons in the main cylinder, an auxiliary cylinder, opposed pistons in the auxiliary cylinder, said cylinders being provided with inlet and exhaust ports, a pair of passages connecting the exhaust ports of the main cylinder with the inlet ports of the auxiliary cylinder, a valve for controlling each of said passages, and means actuated in timed relation to the movement of the pistons for turning the valves to open and close one of the passages and adapted to be manually operated to actuate the valves controlling one of the passages into closed position and opening the valves controlling the other passage.
5. In an engine, the combination of a main cylinder having two sets of exhaust ports, opposed pistons in said cylinder, an auxiliary cylinder, having two sets of inlet ports, opposed pistons in the auxiliary cylinder, two sets of passages connecting the exhaust ports of the main cylinder with the inlet ports of the auxiliary cylinder, a separate set of valves for controlling each set of passages, a reciprocable member for actuating all of the valves in timed relation to the movement of the pistons, and means for manually actuating said reciprocable member to move one set of valves to operative position, and the other set of valves into inoperative position and change the flow of the exhaust from one set of passages to the other set of passages and cause a reversal of the actuation of the engine.
6. In an engine, the combination of a main cylinder, opposed pistons in said cylinder, an auxiliary cylinder, opposed pistons in the auxiliary cylinder, an air pump for supplying air under pressure, an air compression cylinder into which air under pressure from the pump is admitted, means for conducting air from the compression cylinder into the main cylinder at the ends thereof and intermediate its ends, a piston in the compression cylinder controlling the passage leading from said cylinder to the main cylinder, and means for actuating the piston in the compression cylinder in timed relation to the movement of the pistons in the main cylinder.
7. In an engine, the combination of main cylinders, an auxiliary cylinder, opposed pistons in each of said cylinders, passages connecting the exhaust of the main cylinders with the inlets of the auxiliary cylinder, said cylinders being all formed with an air space surrounding them, an air pump for forcing air into the air space, air compression cylinders connected with the air space to receive air therefrom, and having exhaust ports, pistons in said compression cylinders, passages connecting the exhaust ports of the compression cylinders with the main cylinders, and means for reciprocating the pistons in the compression cylinders in timed relation to the movement of the pistons in the main cylinders.
8. In an engine, the combination of main cylinders, an auxiliary cylinder between the main cylinders, opposed pistons in the main and auxiliary cylinders, passages connecting the exhaust of the main cylinder with the intake of the auxiliary cylinder, compression cylinders arranged with their longitudinal axes at right angles to the longitudinal axes of the main cylinders and with one compression cylinder adjacent to each end of the main cylinders, an open passage connecting said compression cylinders with the main cylinders, pistons in the compression cylinders, rods connecting the pistons in the compression cylinders adjacent to one of the main cylinders with the pistons in the compression cylinders which are adjacent to the other main cylinder to cause the pistons to move in unison, valves controlling the passage of the exhaust from the

main cylinders into the auxiliary cylinders, and means actuated by the movement of the pistons in the compression cylinders for actuating said valves.

5 9. In an engine, the combination of main cylinders, an auxiliary cylinder between the main cylinders, opposed pistons in each of the cylinders, a pair of passages connecting each main cylinder with the auxiliary cylinder, a pair of valves controlling each pair of passages, valves for controlling the admission of motive fluid to the main cylinders, a reciprocable member between each pair of valves at each side of the auxiliary cylinder adapted to operate said valves upon reciprocation and connected to simultaneously operate the motive fluid controlling valves, and means for reciprocating said members in timed relation to the movement 20 of the pistons.

10 10. In an engine, the combination of main cylinders, an auxiliary cylinder between the main cylinders, opposed pistons in each of the cylinders, passages connecting the exhaust from the main cylinders with the intake of the auxiliary cylinder, valves for controlling said passages, motive fluid valves for controlling the admission of motive fluid to the main cylinders, compression cylinders connected to the main cylinders, pistons in the compression cylinders, means for actuating the several valves by the movement of the pistons in the compression cylinders, and a fuel pump actuated by the movement 35 of the said valves.

11 11. In an engine, the combination of parallel main cylinders, an auxiliary cylinder between the main cylinders and extending parallel therewith, passages for conducting the exhaust from the main cylinders into the auxiliary cylinders, valves controlling said passages, compression cylinders adjacent to the main cylinders and connected thereto to receive motive fluid therefrom, pistons in the compression cylinders, a rack member actuated by said pistons and engaging and turning the valves, gears on the opposite end of the valves, a rack member to engage said gears, an air pump actuated by said rack member, and an air jacket surrounding the cylinders and communicating with the said compression cylinders.

12 12. In an engine, the combination of main cylinders, an auxiliary cylinder between the main cylinders, passages for conducting the exhaust from the main cylinders into the auxiliary cylinder, valves controlling said passages, valves for admitting motive fluid to the main cylinders, rack bars reciprocable between the main and auxiliary cylinders, gears on the several valves engaging the rack bars, compression cylinders having communication with the main cylinders, pistons in the compression cylinders, means for 60 transmitting motion from the pistons in the

compression cylinders to the several valves to turn the same, a motive fluid pump, an air pump, an air jacket around the several cylinders communicating with the air pump, and means for transmitting motion from the 70 valve members to actuate said pumps.

13. In an engine, the combination of main cylinders, an auxiliary cylinder between the main cylinders, opposed pistons in each cylinder, passages for conducting the exhaust 75 from the main cylinders into the auxiliary cylinders, valves controlling said passages, an air jacket surrounding the cylinders, a pump for forcing air into the air jacket, a compression cylinder adjacent to each main 80 cylinder, a valve for controlling the inlet of air from the jacket into the compression cylinders, a piston in each compression cylinder, an open passage adapted to be closed by the piston connecting each compression 85 cylinder with the adjacent main cylinder, and means operated by the movement of the pistons in the compression cylinders for actuating said valves controlling the passages between the main and auxiliary cylinders.

14. In an engine, the combination of main cylinders, an auxiliary cylinder, opposed pistons in each of the cylinders, passages for conducting the exhaust from the main cylinders into the auxiliary cylinder, valves for controlling the exhaust passages, fuel valves for controlling the admission of fuel to the main cylinders, a reversing fuel inlet valve for each main cylinder, a reversing exhaust 100 valve for each main cylinder, and means for manually actuating the valves controlling the exhaust passages, the fuel inlet valves and the reversing fuel inlet and exhaust valves to cause a reversal of the operation 105 of the engine.

15. In an engine, the combination of parallel main cylinders, an auxiliary cylinder between the main cylinders extending parallel therewith, passages for conducting 110 the exhaust from the main cylinders into the auxiliary cylinder, rotary valves controlling said passages, a series of compression cylinders adjacent to each main cylinder with a compression cylinder adjacent 115 to each end of the main cylinder, and intermediate its ends, said compression cylinders extending transversely of the longitudinal axis of the main cylinders, pistons in the compression cylinders, the pistons in the 120 compression cylinders adjacent to one of the main cylinders being connected to the pistons in the compression cylinders adjacent to the other main cylinder to operate in unison therewith, a rack member actuated 125 by the pistons in the compression cylinders, means on the several rotary valves adapted to be engaged by said rack member to turn the valves, gears on the rotatable valves, reciprocable rack bars for engaging the 130

gears, and means for manually actuating the rack bars.

16. In an engine, the combination of main cylinders, an auxiliary cylinder between the main cylinders, said main cylinders being provided with exhaust ports intermediate their ends, and an auxiliary cylinder being provided with inlet ports at its ends and intermediate its ends, passages connecting the ports of each main cylinder with the inlet ports of the auxiliary cylinder, rotatable valves for controlling said passages, fuel valves for admitting fuel to the main cylinders, gears on all of the valves, a reciprocable rack bar between each main cylinder and the adjacent side of the auxiliary cylinder in engagement with the gears on the valves, a plurality of compression cylinders adjacent to one side of each main cylinder having an open passage communicating with the main cylinder, pistons in the com-

pression cylinders, rods connecting the pistons in the compression cylinders adjacent to one main cylinder with the pistons in the compression cylinders adjacent to the other main cylinder, a rack member connected to said rods to be actuated thereby, means on the several valves engaged by the rack member to actuate the valves, a manually operated shaft extending transversely of the rack bars, gears on said shaft to engage the rack bars, and means actuated by the manual turning of the shaft for controlling the admission of fuel to the main cylinders and the outflow of the exhaust therefrom. 25 30 35

In testimony whereof I affix my signature in presence of two witnesses.

OTTO KERSCHT.
